OIL BURNER CONTROL SYSTEM

David J. Munroe, Racine, Wis., assignor to Webster Electric Company, Racine, Wis., a corporation of Delaware

Application June 30, 1952, Serial No. 296,410

18 Claims. (Cl. 137—116)

This invention relates to an oil burner system and, 15 more particularly, to an improved system for controlling the operation of an oil burner.

Although the use of a by-pass nozzle in a fuel oil burner has many desirable features, it is subject to certain inherent design limitations which make it difficult to utilize such a nozzle in conjunction with a high pressure oil supply system. Prior systems utilizing a by-pass nozzle supply high pressure oil to the nozzle before a control valve in the by-pass system of the nozzle opens with the consequent result that solid oil is injected into the fire chamber. Also, many existing systems utilize a control valve in the by-pass system which is closed prior to closing the valve controlling the supply of high pressure oil to the nozzle whereby large amounts of solid oil are injected into the fire chamber with its attendant disadvantages.

Further, since the back pressure produced in the by-pass line from the nozzle is relatively small in magnitude, it is impossible to utilize self regulating valves therein which are capable of high seating pressures upon closure so that it is impossible to provide a fluid-tight seal between a by-pass reservoir or suction side of the fuel pump and the by-pass portion of the nozzle. The existing oil burner systems utilizing a by-pass nozzle also provide a plurality of separate control valves for the supply line and the by-pass line with a consequent increase in the installation space required. Because of the dependency of the existing systems on back pressure for controlling the operation of the by-pass control valve, it is impossible to provide a control valve for the by-pass line which is operated independently of the back pressure in this line and which is also positively operated in a predetermined sequence with respect to the operation of the control valve in the line supplying oil to the nozzle.

Accordingly, one object of this invention is to provide a control valve system for an oil burner in which the by-pass line from the nozzle is opened prior to opening a valve in the supply line for the nozzle when the pump for the oil burner is actuated.

Another object of this invention is to provide a new and improved control valve system for an oil burner in which the fuel supply line to the nozzle is closed before the by-pass line when the pump or the oil burner is stopped.

A still further object involves the provision of a unitary control valve assembly which is small in size and easily installed in conjunction with the associated fuel oil burner equipment.

Another object of this invention is to provide a control valve for the by-pass line of a by-pass nozzle which is positively operated in a desired sequence relative to the operation of a valve controlling the admission of high pressure oil to said nozzle.

A further object is to provide a control valve assembly for the by-pass line of a by-pass nozzle in which the operation of the by-pass control valve relative to the oper-

2

ation of a control valve in the fuel supply line is independent of the back pressure produced in the by-pass line by said nozzle.

In accordance with these and many other objects, one embodiment of this invention comprises an oil burner nozzle having a fuel supply line and a by-pass line which are each provided with control valves therein. These two control valves are combined into a unitary apparatus together with a pressure regulator valve so that upon an increase in pressure of the fuel oil supplied to the unitary assembly, a flexible diaphragm is moved upwardly to allow a spring loaded valve in the by-pass line to open. The by-pass valve is mechanically interconnected with a valve in the fuel supply line so that upon reaching a predetermined position, the fuel supply valve is opened to admit oil to the nozzle. A further increase in the pressure of the oil supplied to the unitary assembly opens another by-pass line from the valve assembly to an external reservoir so that the nozzle is supplied with fuel oil under a predetermined high pressure. When the pumping means supplying the fuel oil is stopped, the decrease in pressure allows a spring loaded diaphragm to actuate the mechanical interconnection between the two control valves so that the valve controlling the flow of oil to the nozzle is closed and, subsequent thereto a continuing downward movement of the diaphragm actuates the spring loaded control element of the by-pass valve to close the by-pass line, thereby preventing the discharge of solid oil from the nozzle to a fire chamber.

Other objects and advantages of the present invention will become apparent from the following description of an illustrative embodiment thereof in the course of which reference is made to the accompanying drawing wherein:

Fig. 1 is a schematic view of an oil burner system utilizing the improved valve control assembly of this invention;

Fig. 2 is a fragmentary sectional view of a modification of the control valve assembly shown in Fig. 1 which may be utilized in conjunction with the elements of the oil burner system disclosed in Fig. 1;

Fig. 3 is a cross sectional view taken along line 3—3 in Fig. 2, assuming that the entire structure of the control valve assembly is shown in Fig. 2;

Fig. 4 is an enlarged cross sectional view taken along line 4—4 in Fig. 2 again assuming that the complete structure is disclosed in Fig. 2; and

Fig. 5 is an enlarged fragmentary sectional view taken along line 5—5 of Fig. 4 assuming that the complete structure is shown in Fig. 4.

Referring now to the drawing wherein like reference numerals indicate the same elements throughout the several views, and more particularly to Fig. 1 of the drawing wherein is disclosed an oil burner system utilizing the improved control valve assembly of this invention, an oil filter 10 is provided with fuel oil from an external source (not shown). The filtered oil from the filter assembly 10 is drawn through a conduit or pipe 12 by a gear pump 14 and supplied through a conduit 16 to a chamber 17 in a unitary control valve assembly indicated generally as 18. The unitary valve assembly 18, shown operated open in Fig. 1, generally operates to provide a by-pass nozzle 20 having a swirl chamber 29a with a flow of high pressure oil through a conduit 22, and also regulates the return of the fuel oil from the nozzle 20 through a pair of by-pass conduits 24 and 26.

A fuel supply control valve assembly indicated generally as 28, a by-pass control valve assembly indicated generally as 30, and a pressure regulator indicated generally as 32 comprise the unitary valve assembly 18. In order to provide an operation wherein the by-pass valve 30 is opened prior to the opening of the fuel sup-

ply valve 28 when the pump 14 is started, the two valve assemblies 28 and 30 are interconnected adjacent their upper ends by a yoke or plate 34 which is provided with a pair of bearing elements 36 and 37 secured thereto. The upper ball bearing element 36 is resiliently urged in a downward direction by a spring loaded diaphragm assembly 33 of the pressure regulator 32 so that a pair of ball bearing valve elements 38 and 40 associated with the valve assemblies 28 and 30 are urged into engagement with the upper ends of the conduits 22 and 24 to close these conduits.

As the pressure of the fuel oil supplied to the assembly 18 is increased, the diaphragm 33 is moved vertically upward so that a spring 42 urges the valve assembly 30 in an upward direction to pivot or tip the plate 34 in a clockwise direction about the right edge of the plate 34 as a fulcrum, thereby to open the valve 38. Continuing upward movement of the diaphragm 33 permits the plate 34 and valve assembly 28 including the ball valve element 40 to move upwardly and places the conduit 22 in fluid communication with the supply of high pressure oil. In this manner, it is seen that the by-pass conduit 24 is placed in fluid communication with the by-pass conduit 26 and nozzle 20 prior to supplying high pressure oil to the fuel conduit 22 and nozzle 20 when the pump 14 is actuated.

To provide the operation wherein the by-pass valve assembly 30 closes following the closure of the supply valve assembly 28 when the pump 14 is stopped, it is seen that a decrease in the pressure of the fuel oil supplied by the conduit 16 to the assembly 18 permits the diaphragm 33 to move in a downward direction as shown in Fig. 1. This downward movement of the diaphragm 33 moves the valve plate or yoke 34 in a downward direction so that the two valve assemblies 28 and 30 movably carried thereby are also moved in a downward direction. Since the valve assembly 30 is spring loaded by virtue of the provision of spring 42, the valve assembly 28 closes first to cut off the supply of oil to the nozzle 20 whereupon continuing downward movement of the diaphragm 33 under the force of a spring 44 overcomes the resilient action of the spring 42 to pivot the plate 34 in a counterclockwise direction about its right edge to seat the valve element 38 with the upper extremity of the conduit 24 to close the by-pass line from the nozzle 20. In this manner, the invention provides a unitary control valve assembly 18 wherein the fuel supply to the nozzle 20 is stopped before the by-pass from this nozzle is closed.

In order to regulate the pressure of the fuel supplied to the nozzle 20 after the valve assembly 28 is opened, the pressure regulator 32 includes an opening 46 located centrally of the lower portion of the diaphragm 33. As long as the pressure of the fuel oil supplied remains within the range of pressure desired, the ball bearing 36 closes the aperture 46. However an increase in pressure beyond the desired amount moves the diaphragm 33 in an upward direction and, since the upward movement of the yoke 34 is limited by shoulders 48 formed in the body portion of the assembly 18, the aperture 46 is opened to permit a flow of fuel oil to a by-pass reservoir 50 through a conduit 52 and a chamber 54 formed in the assembly 18.

The flow of oil from the by-pass conduit 24 through the by-pass valve assembly 30 to the reservoir 50 is controlled by a needle valve indicated generally as 56 co-operating with a passageway 57. By controlling the flow of oil through the by-pass line 24, it is possible to regulate the back pressure to the nozzle 20. Obviously, the needle valve 56 may be replaced by any well known type of pressure regulator valve.

The pressure at which fuel oil is admitted to the nozzle 20 and, consequently, the pressure at which the plate 34 is moved upwardly under the action of the spring 42 is controlled by adjusting the amount of force applied

by the coil spring 44 to the lower surface of the diaphragm 33. The pressure applied by the coil spring 44 is adjusted by means of a machine screw 60 threadedly engaged within a cover plate 62, the lower end of which is in engagement with a plate 64 having an annular depending flanged edge within which the upper convolution of the spring 44 is received. The force of compression applied by the spring 44 also regulates the pressure at which the valve forming ball bearing 36 is moved out of engagement with the aperture 46 to permit the flow of fuel oil therethrough when the pressure of the fuel oil exceeds that at which it is desired to supply the nozzle 20.

The control valves 28 and 30 are provided with high seating pressures by the coil spring 44 since the force thereof is applied to the ball bearing valve elements 38 and 40 through the bearing valve element 36, plate 34, and the plungers 28a and 30a in the respective valve assemblies 28 and 30.

Figs. 2 to 5, inclusive, disclose a unitary valve assembly 70 similar to the assembly 18 and which includes a pressure regulator 72, a by-pass control valve 74, and a fuel supply control valve 76. The two valve assemblies 74 and 76 are removably positioned in a valve plug 78 which is threadedly received within a body portion or frame 80. The upper ends of the two valve assemblies are movably and mechanically interconnected by a valve control plate 82 (Fig. 5) to produce sequential operation of the two valve assemblies in a manner similar to that described in conjunction with the sequential operation of the two valve assemblies 28 and 30.

The valve assembly 70 is adapted to be connected to a source of high pressure fuel oil through a passageway 84 within which may be received the supply conduit 16 so that a chamber 86 formed in the body 80 is provided with fuel oil under high pressure from the pumping means 14. The fuel supply valve assembly 76 is provided with a counterbore 88 formed in the plug 78 to receive the nozzle fuel supply conduit 22, and the by-pass control valve assembly 74 is provided with a counterbore 90 adapted to receive the by-pass conduit 24.

To produce the sequential operation of the valve assemblies 74 and 76, the high pressure fuel oil within the chamber 86 flows through an aperture 92 formed in the upper end of the plug 78 into a counterbore 94, also formed in the plug 78, as best shown in Fig. 5. When the oil pressure reaches the magnitude at which it is desired to supply fuel oil to the nozzle 20, the fuel oil produces an upward movement of a flanged cap 96 comprising the lower wall of a diaphragm assembly 98 of the pressure regulator 72. The valve control plate 82 having an upstanding portion 100 to which a ball valve element 102 is secured is resiliently urged into engagement with the cap 96 by means of a coil spring 103 interposed between a sleeve 104 (Fig. 2) and a shoulder 105 formed on a valve control plunger 106 in the by-pass control valve assembly 74. The resilient action of the spring 103 is transmitted to the ball bearing 102 through the plunger 106 and the control plate 82 which is movably secured to the plunger 106 by means of a pin 108 secured to the plunger (Figs. 2 and 4) and a somewhat larger slot 110 formed in the plate 82.

Upon upward movement of the cap 96 under the action of the high pressure fuel oil, the plate 82 tips in a clockwise direction (Fig. 2) about a fulcrum point provided adjacent the right hand extremity of the plate 82. A pair of bearings 112 secured to a bottom surface of the plate 82, which prevent skewed deflection of the plate 82, are also lifted out of engagement with the upper surface of the counterbore 94 by this tipping movement. This clockwise tipping of the valve control plate 82, as viewed in Fig. 2, opens the by-pass by moving a valve forming ball bearing 113 out of engagement with the sleeve 104 to open fluid communication between the counterbore 90 of the by-pass line and an annular cavity 114 formed in the body 80 through a passageway

116 in the plug 78. It should be noted that the clockwise tipping of the control plate 82, while opening the valve assembly 74, maintains the high pressure inlet valve assembly 76 in a closed condition.

The fuel supply valve 76 is next opened by continued upward movement of the cap 96 under the control of the high pressure fuel oil since the plate 82 moves in an upward direction and tips in a counterclockwise direction to lift a plunger 118. This plunger is movably secured to the plate 82 by means of a pin 120 (Fig. 4) and slot 122 and in moving upwardly lifts a valve forming ball bearing 122 (Fig. 2) secured to the plunger 118 out of engagement with a sleeve 124.

This opening of the valve 76 places the high pressure fuel oil in the chamber 86 in fluid communication with the nozzle 20 through a fluid circuit comprising the passageway 92, the counterbore 94 and apertures 125 in plate 82, a slot 126 formed axially of the plunger 118, the inner passageway of the sleeve 124, counterbore 88, and conduit 22.

To provide for regulation of the pressure of the fuel oil supplied to the nozzle 20, the plate 82 is limited in the amount of allowable upward movement by an annular ring 128 secured to the inner surface of the counterbore 94. Continuing upward movement of the cap 96, due to an increased pressure of the fuel oil supplied by the pump 14, results in the disengagement of the valve forming ball bearing 102 with a passageway 130 formed centrally of the cap 96. Upon disengagement of the bearing 102 with the passageway 130, fuel oil passes to the by-pass reservoir 50 through the diaphragm assembly 98 and the conduit 52 which is in fluid communication therewith.

The fuel oil by-passed from the nozzle 20 and returned to the valve assembly 70 by the conduit 24 passes upwardly through the counterbore 90 and the inner cavity of the sleeve 104 and thence through the passageway 116 to the annular cavity 114. The oil in the cavity 114 is returned to the by-pass reservoir 50 through a passageway 130 and vertically extending chamber 132 which is in fluid communication with the by-pass conduit 26. The flow of fuel oil from the cavity 114 through the passageway 130 is controlled by a flow adjusting screw 134 which is threadedly engaged within a chamber 136 formed in the body 80. An outer portion of this flow adjusting screw is received within a packing gland 138 to prevent oil seepage along the outer surface of the screw 134, and a centrally recessed cap screw 140 also threadedly received within the body 80 covers the adjusting end of the screw 134 to prevent any undesired interference with a predetermined adjustment of the screw 134. Obviously, the flow adjusting screw 134 and its associated elements may be replaced by anyone of the well known pressure regulator valves.

A coil spring (Fig. 2) 142 resiliently urges the diaphragm assembly 98 and cap 96 downwardly into engagement with the ball bearing 102 and, accordingly, controls the pressure at which fuel oil is admitted to the nozzle 20, and, consequently, the pressure at which the pressure regulator 72 operates to by-pass a portion of the fuel oil in the chamber 86 to the by-pass reservoir 50. Any suitable means, for instance, that disclosed in Fig. 1 of the drawing, may be utilized to regulate the resilient action exerted by the spring 142 on the movable diaphragm assembly 98.

When the pressure of the fuel oil in the chamber 86 is decreased, as produced by stopping the pump 14, the cap 96 moves downwardly as viewed in Figs. 2 and 5 to move the valve control plate 82 in a corresponding direction. To provide a closure of the fuel supply control valve 76 prior to the closure of the by-pass control valve 74, the downward movement of the left hand portion of the plate 82 is retarded by the spring biased plunger 106 to provide a fulcrum about which the plate 82 pivots in a clockwise direction (Fig. 2) during con-

tinuing downward movement of the cap 96, thereby to first depress the plunger 118. This downward movement of the plunger 118 seats the bearing valve element 122 on the sleeve 124 to cut off fluid communication between the nozzle 20 and the high pressure fuel oil supplied by the pump 14. A continuing downward movement of the cap 96 under the resilient action of the spring 142 overcomes the retarding force provided by the coil spring 103 and the plate 82 pivots about the fulcrum provided by the seated plunger 118 to seat the bearings 112 on the upper surface of the counterbore 94 and to seat the bearing valve element 113 on the sleeve 104 to close fluid communication between the by-pass reservoir 50 and the by-pass conduit 24.

The valve assemblies 74 and 76 are capable of utilizing high seating pressures upon being closed inasmuch as the force of the coil spring 142 is transmitted through the cap 96, ball bearing 102, plate 82, and plungers 106 and 118, to the valve bearing elements 113, and 122, thereby to cause these elements to seat firmly against the cooperating sleeves 104 and 124. Also, the valve assemblies 74 and 76 must operate in the desired sequence in view of the positive biasing and retarding action provided by the coil spring 103 associated with the by-pass control valve assembly 74.

In operation, the pump 14 is actuated to supply fuel oil to the valve assembly 70 through the filter member 10 and conduits 12 and 16. When the oil pressure builds up to the point at which the cap 96 is moved vertically upward, as shown in Fig. 2, the by-pass control valve assembly 74 is opened first because of the biasing action of the coil spring 103. Subsequent thereto, continuing upward movement of the cap 96 allows the control plate 82 to move upwardly into engagement with the retaining ring 128 whereupon the plunger 118 is moved upwardly to unseat the bearing valve element 122. The oil in the chamber 86 then passes to the nozzle 20 through passageway 92, counterbore 94, slot 126, counterbore 88, and conduit 22. The by-pass oil from the nozzle 20 is returned to the by-pass reservoir through conduit 24, passageway 116, chamber 114, passageway 130, chamber 132, and conduit 26.

When it is desired to stop the operation of the oil burner system, actuation is removed from the pump 14 to produce a corresponding decrease in the fuel oil pressure within the chamber 86. This decrease in pressure permits the cap 96 to move downwardly under the force applied by the spring 142 to move the bearings 112 into engagement with the upper surface of the counterbore 94. Continuing downward movement of the cap 96 moves the valve bearing element 122 into engagement with the sleeve 124 to prevent a flow of oil to the nozzle 20. A further continuing downward movement of the cap 96 tips the valve control plate 82 to depress the plunger 106 against the retarding action of the spring 103 to firmly seat the valve bearing element 113 in engagement with the sleeve 104 and thereby close off fluid communication between the by-pass reservoir 50 and the by-pass conduit 24 associated with the nozzle 20.

The above described embodiments are merely illustrative of the principles of this invention and numerous other modifications may be devised by those skilled in the art which fall within the spirit and scope thereof.

Having thus described my invention, what I claim as new and desire to secure by Letters Patent of the United States is:

1. Apparatus for use with an oil burner system utilizing a fuel supply line to and a by-pass line from a nozzle, comprising, a unitary valve assembly for controlling the flow of fuel oil through both of said lines, said valve assembly comprising control valve means for controlling the passage of fuel through each of said lines, pivotally supported means interconnecting said control valve means, and means responsive to the pressure of the oil to be supplied to the nozzle for tipping the pivotally sup-

ported means to operate the control valve means in a pre-determined sequence in accordance with the pressure of the oil.

2. Apparatus for use with an oil burner system utilizing a fuel supply line to and a return line from a nozzle, comprising a unitary valve assembly for controlling the flow of oil through both of said lines, said assembly comprising a control valve in each of said lines, one of said control valves being resiliently urged toward an open position, operating means interconnecting the two control valves, and a pressure responsive means in communication with the oil to be supplied to the nozzle and in engagement with the operating means to actuate the operating means to open the resiliently urged valve and then the other valve in response to an increase in the oil pressure.

3. The apparatus defined by claim 2 in which the resiliently urged valve is connected to the return line.

4. The apparatus defined by claim 2 in which the pressure responsive means normally holds both of the valves in a closed condition.

5. Valve apparatus comprising a body defining a chamber, pressure responsive by-pass valve means mounted in chamber, a movably mounted rigid plate positioned in said chamber in engagement with said pressure responsive means, a pair of independent valve means operatively connected to said plate, and means for introducing fluid under pressure into said chamber whereby said pressure responsive means moves said plate to operate said valves.

6. The apparatus defined by claim 5 in which the plate is resiliently urged toward said pressure responsive means.

7. Valve apparatus, including in combination, a body defining a chamber and a by-pass passageway, pressure regulating means having a first valve adapted to place said chamber and said passageway in fluid communication, second valve means, and valve operating means movably mounted on said body with said operating means in a force transmitting relation with said regulating means for operating said second valve means, said force transmitting relationship maintaining said first valve closed, said regulating means and said operating means being movable in said force transmitting relationship to operate said second valve means, said regulating means and said operating means also being movable out of said force transmitting relationship whereby said first valve places said chamber and said by-pass in fluid communication.

8. A unitary pressure regulator and valve operator for use in systems utilizing fuel supply, return and by-pass lines comprising a body defining a chamber, fluid pressure regulating means having first valve means in fluid communication with said chamber and said by-pass line, said first valve means being closed over a first range of pressures and open to by-pass fluid to said by-pass line from said chamber in a second fluid pressure range, second valve means for controlling the flow of fluid through said supply and return lines, valve operating means movably mounted on said body and actuated by said regulating means through said first pressure range to actuate said second valve means, and means for admitting fluid having a pressure in said first and second ranges to said chamber.

9. The apparatus defined by claim 8 in which an increase of pressure in said first pressure range actuates said second valve means to open said return line and thereafter to open said supply line.

10. The apparatus defined by claim 8 in which a decrease of pressure in said first pressure range actuates said second valve means to close said supply line and thereafter to close said return line.

11. The apparatus defined by claim 8 in which the body is formed with means placing the chamber in fluid communication with the supply line.

12. Valve apparatus, including in combination, a body defining a chamber having a fluid inlet and an opening, said opening including detachable connecting means, pres-

sure responsive means in said chamber and in fluid communication with said inlet, and an insert element including valve means and valve operating means controlled by said pressure responsive means, said insert element being mounted in said opening by said detachable connecting means.

13. A control valve for use in a fuel oil burner system, comprising, a body defining a chamber, a fuel supply port opening through said body into said chamber, a bypass conduit through said body, a valve disposed within said chamber for controlling the passage of fluid between said chamber and said bypass conduit, a pressure responsive member communicating with said chamber for actuating said valve in response to the pressure in said chamber, a nozzle fuel supply passageway in said body communicating with said chamber, a fuel supply valve supported by said body and positioned to control the flow of fuel from said chamber to said passageway, a nozzle bypass duct through a portion of said body, a nozzle bypass valve in said duct for controlling the passage of fuel therethrough, spring means associated with said nozzle bypass valve for biasing it in an open position, and a valve operating member actuated by said pressure responsive member for sequentially opening said last-named valves, said spring being operative to maintain said bypass valve open at a chamber pressure less than that required to actuate said valve operating member to open said fuel supply valve.

14. A fluid control valve comprising a body having a pressure chamber, a port for the emission of pressurized fluid into said chamber, a bypass port for returning excess fuel from said chamber to a reservoir, a nozzle supply port in said body for conducting fuel from said chamber to a fuel nozzle, a nozzle bypass port in said body for returning fuel from said nozzle, a valve in the bypass port, a valve in the nozzle supply port, a valve in the nozzle bypass port, means including a flexible diaphragm for sequentially controlling the passage of fuel through each of said ports as the fuel pressure in said chamber varies throughout a predetermined range, and means for supplying a biasing force to said nozzle bypass valve to urge it toward an open position thereby to insure opening of said bypass port at a chamber pressure less than that required to open said nozzle supply port.

15. A fluid control device comprising a body having a pressure chamber, an inlet port, a nozzle supply port and a nozzle bypass port, a valve controlling said supply port, a valve controlling said bypass port, means for normally urging said valves into positions to close said ports, a flexible diaphragm in said chamber for urging said means out of operative engagement with said valves when the pressure in said chamber exceeds a predetermined value, and means acting on said valve controlling said bypass port in opposition to the force exerted thereon by said first-named means, whereby said bypass port is opened at a chamber pressure less than that required to open said supply port.

16. Apparatus of the type described, comprising, a body having a pressure chamber, an inlet port to said chamber, an outlet port from said chamber, a valve controlling said outlet port, a nozzle bypass duct through said body, a nozzle bypass valve controlling said bypass duct, an operating member secured at spaced locations to an operating element of each of said valves, means exerting a force on said operating member to normally close said valves, means exerting a force on only one of said valves in opposition to the force exerted thereon by said first named means, and pressure responsive means disposed in said chamber for counteracting the force exerted on said operating member by said first named means when the pressure in said chamber exceeds a predetermined value.

17. A control valve for oil burners, comprising, a body having a pressure chamber, an inlet port to said chamber, a bypass port for returning fuel from said chamber to a

reservoir, an outlet port for conducting fuel from said chamber to a fuel nozzle, and a nozzle bypass duct for returning fuel from said nozzle to said reservoir, a valve for controlling the flow of fuel from said chamber to said bypass port, a valve for controlling the flow of fuel from said chamber to said outlet port, a valve for controlling the flow of fuel through said nozzle bypass duct, a flexible diaphragm positioned in said chamber and responsive to the pressure of the fuel in said chamber for opening each of said valves, resilient means for normally urging said nozzle bypass valve into an open position, and means for normally urging each of said valves into a closed position.

18. A unitary control means for use with a burner system including both a fuel supply and a fuel supply line to and a bypass line from a nozzle comprising a chamber provided with fuel under pressure from said supply, independently movable valve means for controlling

the passage of fuel through each of said lines, pressure responsive means positioned within said chamber to be controlled by the pressure of the fuel therein, and a mechanical link operatively connected to the pressure responsive means including separate means movably connecting each of the two valve means to said link to operate one of said valve means and then another of said valve means in a predetermined sequence under the control of changing fuel pressure.
